(57) **CLAIM**

The ornamental design for a shoe, as shown and described.

DESCRIPTION

FIG. 1 is a top, left, and front perspective view of an ornamental design for a shoe;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a bottom, right, and front perspective view thereof; and,

FIG. 9 is a bottom, right, and rear perspective view thereof. The dash-dash-dash broken lines are included for the purpose of illustrating portions of the shoe that form no part of the claimed design. The oblique shade lines depict a transparent or translucent surface or material. The even dashed broken lines on the claimed portions of the shoe upper depict stitching, which does not form part of the claimed design.
